DESIGN FOR A COMBINATION AUTOMOBILE FENDER SHIELD AND SIDE BUMPER OR SIMILAR ARTICLE

Frederick W. Wohlfeld, Detroit, Mich., assignor
to Houdaille - Hershey Corporation, Detroit,
Mich., a corporation of Michigan

Application April 14, 1941, Serial No. 100,368

Term of patent 7 years

To all whom it may concern:

Be it known that I, Frederick W. Wohlfeld, a citizen of the United States and a resident of the city of Detroit, in the county of Wayne and State of Michigan, have invented a new, original, and ornamental Design for a Combination Automobile Fender Shield and Side Bumper or Similar Article, of which the following is a specification, reference being had to the accompanying drawing, forming a part thereof.

On the drawing:

Figure 1 is an elevational view of the combi-

nation automobile fender shield and side bumper showing my new design in which the side bumper portion is the shorter of the two overlapping members as best illustrated in Figure 2, a fender being illustrated in dotted lines for illustrative purposes only; and

Figure 2 is a top plan view thereof.

I claim:

The ornamental design for a combination automobile fender shield and side bumper or similar article, as shown and described.

FREDERICK W. WOHLFIELD.
